RAILWAY TRACK SWITCH CONTROLLING APPARATUS

Arthur W. Fisher, Forest Hills, Pa., assignor to
The Union Switch & Signal Company, Swiss-
vale, Pa., a corporation of Pennsylvania

Application March 15, 1935, Serial No. 11,298

4 Claims. (Cl. 246—219)

My invention relates to railway track switch controlling apparatus, and particularly to apparatus of the type involving a polarized relay controlled by a manually operable lever or other suitable device, under given traffic conditions, which relay in turn causes movements of the switch to normal and reverse positions.

One feature of my invention is the provision of a novel and improved arrangement for the control of the polarized relay, and also of a neutral relay, by the manually operable device, under the given traffic conditions, which neutral relay in turn controls, in part, the polarized relay. My invention is an improvement upon the apparatus disclosed and claimed in a co-pending application, Serial No. 695294, for Interlocking control apparatus, filed October 26, 1933, by Earl M. Allen and Howard A. Thompson.

I will describe one form of apparatus embodying my invention, and will then point out the novel features thereof in claims.

The accompanying drawing is a diagrammatic view, showing one form of apparatus embodying my invention.

Referring to the drawing, the reference characters **1** and **1^a** designate the track rails of a stretch of railway track **Y** which is divided by insulated joints **2** into sections **B—C**, **C—D** and **D—E**. Each of these sections is provided with a track circuit, such for example as is shown for section **D—E**, comprising a battery, designated by the reference character **3**, connected across the rails adjacent one end of the section, and a relay, designated by the reference character **T**, connected across the rails adjacent the opposite end of the section.

Located in section **D—E** is a switch **H¹** for connecting track **Y** with a second track **Z**. Switch **H¹** is operated by a suitable switch mechanism **M**.

In section **C—D** there is a similar switch **H²**.

At point **C**, a signal **S** is shown for controlling eastbound traffic movements, that is, traffic movements from left to right, as shown in the drawing, over switches **H¹** and **H²**.

Switch mechanism **M** is controlled by neutral contacts **24**, **27**, and by polar contacts **25**, **26** of a polarized switch control relay **m**.

Relay **m** is controlled by a neutral lock relay **R**, an approach or stick locking relay **P**, a route locking relay **V**, track relay **T**, and normal and reverse switch lever repeater relays **f** and **g**, respectively. A resistor **16** is connected across the winding of relay **m** in order to make relay **m** slow in releasing when its control circuit is opened.

Relay **R** is controlled by relays **m**, **P**, **V**, **T**, **f** and

g. A second resistor **14** is connected across the winding of relay **R**, through contacts of relays **P**, **V** and **T**, in order to make relay **R** slow in releasing if its control circuit becomes opened while the front contacts of relays **P**, **V** and **T** are closed. If any one of the relays **P**, **V** and **T** becomes deenergized, relay **R** will release quickly.

Approach or stick locking relay **P** may be controlled in any suitable manner such, for example, as shown for relay **L** in a Patent No. 1,956,851, which was granted May 1, 1934, to C. A. Brooks and J. M. Pelikan, for Railway traffic controlling apparatus. The manner in which relay **P** is controlled prevents an operator or leverman from changing the position of switch **H¹** until a measured period of time has elapsed after signal **S** has been caused to indicate "stop", if an eastbound train has entered section **B—C** while signal **S** is indicating caution or proceed.

Route locking relay **V** is so controlled that at times switch **H¹** cannot be operated while an eastbound train occupies section **C—D**.

Normal and reverse switch lever repeater relays **f** and **g** are controlled by a switch lever designated by the reference character **k**.

Lever **k** has a normal position **n**, and a reverse position **r**. Lever **k** operates a contact member **4** which, when lever **k** is moved to its **n** position in which it is shown in the drawing, completes a circuit for energizing relay **f**, and which, when lever **k** is moved to its **r** position, completes a circuit for energizing relay **g**.

I will now trace the operation of the form of apparatus, embodying my invention, which is shown in the accompanying drawing.

As shown in the drawing, all parts are in the normal condition, that is, track relay **T** is energized; switch lever **k** is in its **n** position; switches **H¹** and **H²** are in the normal position; signal **S** is indicating stop; relays **f**, **m**, **R**, **P** and **V** are energized; and relay **g** is deenergized.

With lever **k** in the normal position **n**, relay **f** is energized by its pick-up circuit passing from terminal **x** of a suitable source of current not shown in the drawing, through contact member **4** of lever **k** in its **n** position, and the winding of relay **f** to terminal **o** of the same source of current. A stick circuit is also closed for relay **f**, passing from terminal **x**, through contact **5** of relay **g**, contact **6** of relay **f**, and the winding of relay **f** to terminal **o**.

With relays **P**, **V**, **T** and **f** energized, and with relay **m** energized by a circuit which will be traced hereinafter, relay **R** is energized by a circuit passing from terminal **x**, through the front point of

contact 7 of relay f, back point of contact 8 of relay g, contact 9 of relay T, contact 10 of relay V, contact 11 of relay P, winding of relay R, contact 12 of relay m, and contact 13 of relay m in its normal position to terminal o.

With relays R, P, V, T and f energized, relay m is energized by current of normal polarity passing from terminal x, by the path previously traced for the circuit for relay R as far as contact 11 of relay P, thence passing through the front point of contact 15 of relay R, winding of relay m, front point of contact 17 of relay R, contact 18 of relay P, contact 19 of relay V, contact 20 of relay T, back point of contact 21 of relay g, and the front point of contact 22 of relay f to terminal o.

With relay m energized by current of normal polarity, contacts 25 and 26 of relay m are closed in their normal position, and contacts 24 and 27 of relay m are also closed in a circuit for causing mechanism M to operate switch H¹ to its normal position.

I will assume that, with all parts of the apparatus thus in the normal condition, the leverman desires to reverse switch H¹. He will therefore move lever k to its reverse position r, thereby completing a pick-up circuit for energizing reverse lever repeater relay g, this circuit passing from terminal x, through contact member 4 of lever k in the r position, and the winding of relay g to terminal o. Relay g, upon becoming energized, opens its contact 5, thereby breaking the stick circuit for relay f which is thus deenergized. Relay f, upon becoming deenergized, permits its contact 5 to close and thereby complete a stick circuit for relay g passing from terminal x, through contact 5 of relay f, contact 6 of relay g, and the winding of relay g to terminal o.

During the interval between the opening of contact 8 of relay g at its back point, and the closing of contact 22 of relay f at its back point, the circuits for relays m and R are open. Also, during this interval, the winding of relay R is included in a shunt path passing from the right-hand terminal of relay R, as shown in the drawing, through resistor 14, contact 9 of relay T, contact 10 of relay V, contact 11 of relay P, and the winding of relay R. On account of this path being closed, relay R is slow enough in releasing to retain its contacts 15 and 17 closed at their front points during this interval.

The front contacts of relay m may, however, open during this interval at the end of which a reverse energizing circuit will be closed for relay m, passing from terminal x, through the back point of contact 7 of relay f, front point of contact 21 of relay g, contact 20 of relay T, contact 19 of relay V, contact 18 of relay P, front point of contact 17 of relay R, winding of relay m, front point of contact 15 of relay R, contact 11 of relay P, contact 10 of relay V, contact 9 of relay T, front point of contact 8 of relay g, and the back point of contact 22 of relay f to terminal o.

The different parts of the apparatus are so designed that relay R not only bridges the interval between the opening of the back point of contact 8 of relay g and the closing of the back point of contact 22 of relay f, but that it also bridges the further interval until contact 13 of relay m is closed in its reverse position and contact 12 of relay m is again closed. A reverse energizing circuit will then be completed for relay R, which, on account of the current flowing through the winding of relay R in the opposite direction from the current in the previous circuit for relay R, causes

relay R to open its contacts at the front points and then again quickly close them. This circuit passes from terminal x, through contact 13 of relay m in the reverse position, contact 12 of relay m, winding of relay R, contact 11 of relay P, contact 10 of relay V, contact 9 of relay T, front point of contact 8 of relay g, and the back point of contact 22 of relay f to terminal o.

On account of resistor 16 being connected across the winding of relay m, this relay is slow enough in releasing to bridge the open circuit period of contacts 15 and 17 when the reverse energizing circuit is closed for relay R.

With relay m energized in the reverse direction, a circuit will now be completed for mechanism M, passing from terminal x, through contact 24 of relay m, contact 25 of relay m in the reverse position, mechanism M, contact 26 of relay m in the reverse position, and contact 27 of relay m to terminal o. Mechanism M will therefore move switch H¹ to its reverse position.

When the leverman desires to return switch H¹ to the normal position, he will return lever k from its r to its n position, causing relay f to again become energized by its pick-up circuit previously traced. Relay f, upon becoming energized, opens its contact 5, thereby breaking the stick circuit previously traced for relay g. The operation of the apparatus for causing mechanism M to return switch H¹ to its normal position can be readily understood in view of the foregoing description of the operation of the apparatus for causing mechanism M to move switch H¹ to its reverse position.

I will next assume that, with all parts of the apparatus again in the normal condition, the leverman clears signal S for an eastbound traffic movement over switches H² and H¹. The clearing of signal S causes locking relay P to be deenergized.

Relay P, upon becoming deenergized, permits its contact 11 to open, thereby breaking the circuit first traced for relay R. The shunt path previously traced through resistor 14 is now open at contact 11 of relay P, and hence relay R permits its contacts 15 and 17 to open quickly at the front points and close at the back points.

On account of resistor 16 being connected across the winding of relay m, relay m will be slow enough in releasing to bridge the open circuit period between the opening of contacts 15 and 17 at their front points and the closing of these contacts at their back points, and hence front contacts 12, 24 and 27 of relay m will not open during this interval. At the conclusion of this interval, a stick circuit for relay m will be closed, passing from terminal x, through contact 23 of relay m in its normal position, back point of contact 15 of relay R, winding of relay m, back point of contact 17 of relay R, and contact 13 of relay m in its normal position to terminal o. Relay m, being now energized by current of the same polarity as before, will retain its neutral contacts closed, and will keep its polar contacts closed in the same positions as before.

I will further assume that an eastbound train now enters section B—C, and afterward proceeds into section C—D, and then into section D—E. While the train is in section C—D, relay V will be deenergized, and while the train is in section D—E, relay T will be deenergized. From an inspection of the drawing, it will be noted that as long as any one of the relays P, V, and T is deenergized, both circuits previously traced for relay

R will be open, and hence relay m will continue energized by the stick circuit previously traced.

I will now assume that while any one of the relays P, V and T is deenergized, the leverman, by mistake, attempts to reverse switch H¹ by moving lever k to its r position. As previously stated, relay R cannot become energized as long as any one of the relays P, V and T is deenergized. I will further assume that the leverman permits lever k to remain in its r position, and that while lever k is in its r position, such of the relays P, V and T as are deenergized again become energized. With relay g energized, and with relay f deenergized on account of lever k being in its r position, the winding of relay R will now be included in a closed path which is the same as the second circuit traced for relay R except that, instead of passing from terminal x, through contact 13 of relay m in its reverse position, this path includes contact 13 of relay m in its normal position, and hence both ends of the path are connected to terminal o and relay R will not become energized.

In order to energize relay R, the leverman must return lever k to its n position, thereby causing relay f to again become energized and to complete the circuit first traced for relay R. When relay R has thus been energized, the leverman can reverse switch H¹ by the procedure previously described.

It follows that any change in the position of lever k while any one of the relays P, V and T is deenergized, will be ineffective to cause an operation of switch H¹ after all of the relays P, V and T are again energized. In other words, control by lever k while any one of the relays P, V and T is deenergized, cannot be stored for causing an operation of switch H¹ when all of the relays P, V and T are again energized.

From a consideration of the foregoing description and the accompanying drawing, it follows that, in apparatus embodying my invention, a neutral lock relay R and a polarized switch control relay m are controlled, under given traffic conditions, by normal and reverse manually controlled contacts; each of the relays m and R is controlled by a front contact of the other; relay m is also controlled at times by back contacts of relay R; relay R is arranged to be slow-releasing if it becomes deenergized under the given traffic conditions, but is quick-releasing if it becomes deenergized under other traffic conditions; and relay m is arranged to be slow-releasing at all times. On account of relay R being controlled by a polar contact of relay m, the apparatus does not permit the storage of switch control.

Although I have herein shown and described only one form of railway track switch controlling apparatus embodying my invention, it is understood that various changes and modifications may be made therein within the scope of the appended claims without departing from the spirit and scope of my invention.

Having thus described my invention, what I claim is:

1. In combination, a railway track switch, a polarized relay having a neutral contact as well as polar contacts, a neutral relay, a traffic contact controlled by traffic conditions and arranged to be closed only when said traffic conditions are suitable for said switch to be moved from one of its extreme positions to the other, normal and reverse manually controllable contacts, a source

of current, a normal circuit including said traffic contact and said source of current and controlled by said normal manually controllable contact as well as by said neutral contact and a normal polar contact of said polarized relay for energizing said neutral relay by current of normal polarity, a reverse circuit including said traffic contact and said source of current and controlled by said reverse manually controllable contact as well as by said neutral contact and a reverse polar contact of said polarized relay for energizing said neutral relay by current of reverse polarity, a resistor, a shunt path for the winding of said neutral relay including said resistor and said traffic contact, normal and reverse pickup circuits for said polarized relay including said normal or reverse manually controllable contacts respectively and said traffic contact as well as said source of current and controlled by a front contact of said neutral relay, normal and reverse stick circuits for said polarized relay including one of its own normal or reverse polar contacts respectively and controlled by a back contact of said neutral relay, a second resistor, a shunt path for the winding of said polarized relay including said second resistor, and means controlled by normal and reverse polar contacts of said polarized relay for operating said switch to normal and reverse positions respectively.

2. In combination, a railway track switch, a polarized relay, a neutral relay, a traffic contact responsive to traffic conditions and closed when said traffic conditions are suitable for said switch to be moved from one of its extreme positions to the other, a normal and a reverse manually controllable contact, a normal and a reverse energizing circuit for said neutral relay controlled by said normal and reverse manually controllable contacts respectively and including said traffic contact and controlled by neutral and polar contacts of said polarized relay, a resistor, means comprising a shunt path including said resistor and said traffic contact for at times rendering said neutral relay slow in releasing, normal and reverse energizing circuits for said polarized relay controlled by said normal and reverse manually controllable contacts respectively and by said traffic contact as well as by front contacts of said neutral relay, normal and reverse stick circuits for said polarized relay controlled by one of its own polar contacts in the normal and reverse position respectively and by back contacts of said neutral relay, and means controlled by polar contacts of said polarized relay in normal and reverse positions for operating said switch to normal and reverse positions respectively.

3. In combination, a railway track switch, a polarized relay, a neutral relay, manually controllable means, circuits controlled by neutral and polar contacts of said polarized relay and by said manually controllable means for energizing said neutral relay only under given traffic conditions, a resistor, means including said resistor for at times rendering said neutral relay slow in releasing under said given traffic conditions, normal and reverse energizing circuits for said polarized relay controlled by said normally controllable means and closed only when front contacts of said neutral relay are closed and only under said given traffic conditions, normal and reverse stick circuits for said polarized relay controlled by normal and reverse polar contacts respectively of said polarized relay and by back contacts of said neutral relay, and means controlled by normal and reverse polar contacts of said po-

larized relay for operating said switch to normal and reverse positions respectively.

4. In combination, a railway track switch, a polarized relay, a neutral relay, manually controllable means, circuits controlled by said manually controllable means for energizing said neutral relay only under given traffic conditions and controlled by said polarized relay to prevent storage of control, means comprising a shunt path 10 for at times rendering said neutral relay slow in releasing under said given traffic conditions,

normal and reverse energizing circuits for said polarized relay controlled by said manually controlled means and by front contacts of said neutral relay, normal and reverse stick circuits for said polarized relay controlled by normal and reverse polar contacts respectively of said polarized relay and by back contacts of said neutral relay, and means controlled by said polarized relay for operating said switch to normal and reverse positions respectively.

5

ARTHUR W. FISHER.
